UNITED STATES PATENT OFFICE.

RALPH A. ROHRER, OF ALTOONA, PENNSYLVANIA.

EXERCISING DEVICE.

1,014,774.

Specification of Letters Patent.

Patented Jan. 16, 1912.

Application filed February 4, 1911. Serial No. 606,483.

To all whom it may concern:

Be it known that I, RALPH A. ROHRER, a citizen of the United States, residing in the city of Altoona, county of Blair, and State of Pennsylvania, have invented new and useful Improvements in Exercising Devices, of which the following is a specification.

My invention consists of an exercising device which is simple and economical of construction, as well as compact, and can readily be transported from place to place and operated without the usual difficulties of attaching the same to projections in walls, doors, etc.

15 My device can be rolled up and put in one's pocket or in an ordinary traveling man's grip.

A further object of my invention is to reduce the cost of manufacture so that it 20 will be within the reach of everybody.

With this and other objects in view my invention consists of the mechanism illustrated in the accompanying drawing, in which—

Figure 1 is a perspective view of the entire device. Fig. 2 is a perspective view of one of the hand grips. Fig. 3 is an elevation, partly in section, of one of the hand grips.

Similar numbers refer to similar parts 30 throughout the drawing.

My device consists of an elastic cord "1," which passes around the sheave of the pulley "3," and has means for attaching it to the hand grips "2," "2" at each end. Any 35 form of fastening means can be used, but I prefer to have a hook on the hand grip "2," such as is shown at "11," and an eye attached to each end of the cord. The sheave "3" is provided with a swivel "4" and to this 40 swivel "4" is attached a hook "5." This can be done by having the hook and swivel integral, as shown, or it may be done by having an eye attached to the swivel and the hook attached to the eye of the swivel. It

45 is my purpose to provide three sizes of hooks with each device so that the hook will fit any door hinge projection or other permanent fastening in the room. My object in doing this is to avoid the necessity of driving

50 nails, screw-eyes or hooks into the walls, so that the exercising device can be used in any room where the party desiring to take the exercise may be. The elastic cord "1" can be replaced by a rolled spring, or

55 similar device. The main frame of the hand grip is made of one piece of wire doubled

in the middle and bent up in the shape of a hook, as shown at "11." It is then turned outwardly in opposite directions, as shown at "10," "10" Fig. 3, and then upwardly 60 to form the sides "6," "6." It is next bent at right angles to the sides "6," "6," so as to form the upper cross bar "7." Instead of merely meeting in the center, the two ends extend over each other and each of 65 them is cut out so as to form a semi circular piece in order that the two ends over-lapping will make the same sized bearing as the wire itself. Balls of wood, rubber or other material, such as shown at "17" Figs. 70 2 and 3, are loosely held on the cross bar "7" and are freely rotatable independent of each other. This forms the main grip for the hand. Near the center of the grip is another cross bar "14," which has the upper 75 ends of springs "12," "12" attached to it by means of coils, which are prevented from slipping off the cross bar by washers "15," or integral pieces "15," on the ends of the cross bar "14." The preferable way of at- 80 taching this cross bar is to form it with a head at one end and then pass it through the eye of one of the springs "12," slip a number of balls "18," which are similar to those shown at "17," over the bar, pass 85 the other end through the eye on the opposite spring "12," and secure a washer "15" by riveting on the opposite end of the bar "14." This will not only form a grip for the springs "12," "12," but will also act as 90 a holding means for retaining the side bars "6," "6" in position and prevent spreading. The two end balls "18" are cut out in the center in order to allow free rotation over the washers "15," and the ends of the 95 springs "12." The remaining balls are freely rotatable on the bar "14," together or independent of each other. The lower end of the springs "12," "12" are secured to the cross bar "10."

100 From this description it will be readily seen that in using the exercising device the hook "5" is put over the upper end of the door hinge for instance, and the cross bar having the balls "17" grasped in each hand. 105 In this way it can be used as the ordinary form of exercising device, and on account of the swivel "4" motions in all directions are freely made without causing twisting of the elastic. By attaching the hook to the upper 110 hinge you can get the benefit of the downward pull, the same as you get the benefit of

the upward pull by attaching it to the lower hinge of the door.

If it is desired to use the gripping muscles at the same time as the muscles of the arm and chest, the operator grasps the balls "18" on the cross bar "14" with his fingers and hooks his thumb over the balls "17" on the cross bar "7." The springs "12", "12" operate independent of the elastic cord "1", and by this means the gripping muscles can be exercised at the same time as the muscles of the arm and chest. The object of using the balls and making them independently rotatable is to prevent friction on the fingers and hand, which causes blisters and callous to form.

Another use of the hand grip is for massage. In doing this the grip is detached from the elastic cord and grasped with the thumb hooked over the cross bar "10" and the fingers over the balls "18". The balls "17" are then held in contact with the parts of the body to be massaged and the device moved up and down.

I am aware that prior to my invention there have been a number of exercising devices made which employ an elastic cord or spring. They also use hand grips of differ-

ent construction from that shown in this case. Therefore, I do not claim this broadly, but

I claim—

1. In a hand grip for exercising devices, the combination of a frame, a plurality of balls rotatably mounted upon one end of said frame, a movable cross bar intermediate the ends of said frame, a plurality of balls rotatably mounted upon said cross bar and elastic connections between the ends of the movable cross bar and the end of the frame, substantially as described.

2. In a hand grip for exercising devices, the combination of a frame, a plurality of balls rotatably mounted upon one end of said frame, a movable cross bar intermediate the ends of said frame, balls rotatably mounted upon said cross bar, springs surrounding the sides of said frame and attached at one end to the end of the frame and at the other end to the movable cross bar, thereby holding the sides of the frame together, substantially as described.

RALPH A. ROHRER.
